UNITED STATES PATENT OFFICE

IRVING H. PECK, OF DERBY, CONNECTICUT, ASSIGNOR TO THE STERLING PIN COMPANY, OF DERBY, CONNECTICUT

HAIRPIN

Application filed October 27, 1931. Serial No. 571,372.

This invention relates to the general class of hairpins and has particular reference to a pin to be used with long rather than bobbed hair, but having, nevertheless, certain useful characteristics which are found in some of the so-called bobbed hairpins.

Generally speaking, one object of the invention is to combine in a single structure a maximum number of improved features and 10 advantages which make the pin more useful than previous pins.

It is an object of my invention to provide a pin which holds itself very securely in place in the hair, which has a spring action so that 15 it will grasp the long hairs firmly, which can be readily inserted into the hair without the necessity of spreading the legs widely apart as in ordinary bobby pins so that the pin can be easily placed in the desired position by 20 pushing it lengthwise into place without the need for any substantial separation of the legs, which is invisible to a large extent when it has been placed in the hair so that it does not detract from the appearance of the coif- 25 fure, which has ends formed or shaped in such a way that they will readily pass into the body of hair, which is made of such a class of material that it can be cheaply manufactured, and which can be readily produced by the use 30 of suitable machines from the material selected for its manufacture.

To these and other ends the invention consists in the novel features and combinations of parts to be hereinafter described and 35 claimed:

In the accompanying drawing:

Fig. 1 is a side elevation on a considerably enlarged scale of a hairpin embodying my improvements;

Fig. 2 is a view similar to Fig. 1 showing the pin as it appears when the legs are grasped at their extremities and pulled away from each other;

Fig. 3 is an edge view of the pin shown in Figs. 1 and 2;

Figs. 4 and 5 are sections, respectively, on line 4—4 and line 5—5 of Fig. 1; and

Fig. 6 is an end view of the pin looking toward the fold or butt end.

As shown in the drawing, the improved pin

of my invention is for the most part symmetrical in form by reason of the fact that parts on one side of a longitudinal center line have corresponding parts located on the opposite side of such line. To an extent, however, the pin is asymmetrical, because the free end portion of one leg is somewhat shorter than the free end portion of the opposite leg, which makes one of the legs of the pin somewhat longer than the other. The 55 pin is constructed of relatively inexpensive round wire, but in certain portions of its structure this wire is shaped to form flattened web-like portions.

In the drawing, the short leg of the pin is 60 indicated by reference character 10 and the long leg by reference character 11. Short leg 10 has a short end portion 12 formed by flattening the wire, and leg 11 has a 65 similar but longer flattened end portion 13. The extremities of these end portions are rounded, as shown at 14 in Fig. 3, so that they can readily penetrate the hair without catching therein. The end portions 12 and 13 are divergent, as shown in Fig. 1, and 70 normally occupy the position shown in that view by reason of the springiness of the legs. Back of the end portions 12 and 13 the legs are bent to form zigzag portions (these portions being of round cross-section) which 75 present a number of projections that are in registry with each other. The projections on leg 10 are indicated at 10^a in Fig. 2, and the projections on leg 11 are indicated at 11^a in the same figure. Each projection 10^a 80 is adapted to contact with the correspondingly located registering projection 11^a. By forming the legs in the manner described, a number of substantially rhomboidal recesses or openings such as 15, 16, 17, 18 and 19 are presented by the hairpin when the legs are in the normal contacting position, these recesses or openings being adapted to 85 receive and retain hair and the shape of the pin being such as to resist displacement in the hair when the pin has been once positioned. In the rear of the recess or opening 19 the legs 10, 11 are provided with similar 90 oppositely located web portions or flats 20, 21 which are produced by flattening and thin- 100

ning down the leg portions through a noticeable part of their length at the rear of the corrugated leg portions and in that portion of the pin which may be described generally as the looped or folded portion thereof. However, in the rear of the flattened portions 20, 21 the cross-section of the pin is round or substantially round, as shown at 22, and preferably this portion 22 of round 10 cross-section is extended not only over the extreme butt end of the pin, but also to some degree in advance of this extreme butt end, so that while in the portions 20, 21 the body of the pin is widened through, say, a little 15 more than half the distance from the corrugated portion to the extreme inner end of the pin, the narrow rounded portion is located partly in the longitudinally disposed somewhat convergent loop portions located back 20 of the corrugated portions.

By providing the flattened portions 20 and 21 or their equivalents at the rear of the corrugated shank portions of the pin, the article 25 is given considerable springiness and has an effective clamping action on the hair so that the corrugated portions are firmly pressed against the hair from opposite sides by the spring in those portions of the legs which are disposed toward the butt. The flat portions 30 20, 21 are very effective in imparting a spring clamping action to the leg portions, and the leg portions are so formed as effectively to resist longitudinal dislocation in the hair. The springy characteristic of the 35 pin is well illustrated in Fig. 2, which shows the positions taken by the legs when the free extremities thereof are grasped and separated. It will be observed that when this is done the separation of the legs is strongly 40 resisted by the spring portions 20, 21, which are only slightly displaced (separated) from the position shown in Fig. 1. Upon release of the legs when in the position shown in Fig. 2, they return to the position shown in 45 Fig. 1 and this will occur when the legs are separated an indefinite number of times, owing to the inherent resiliency of the pin which will persist during long periods of use.

The improved pin serves very satisfactorily 50 for use in coiffures of long hair because owing to the formation and disposition of the end portions 12, 13, the pin can be very readily inserted into the hair without a substantial amount of separation of the legs being necessary. The pin will be securely held in the 55 hair owing to the clamping action which is provided as above described, and owing to the formation of the leg portions. As the corrugated leg portions are of round cross-section and relatively attenuated, they are to a large degree invisible when the pin is in 60 position in the coiffure, and this, of course, is very desirable. The butt end portion of the pin is also constructed of material having 65 a round cross-section and this portion

of the pin is likewise substantially invisible when the pin is in position in the hair. Thus the amount of metal which is disclosed to view when the hair has been dressed is reduced to a minimum. The pin can be produced from round stock which is comparatively inexpensive and can be readily made in quantity by hairpin machines which are not unduly complicated in their construction. 70

Various changes can be made in the details of the structure as herein described without departing from the scope of my invention as defined in the claims. 75

What I claim is:

1. A hairpin comprising a single piece of material of round cross-section folded intermediate of its ends to form two legs, both of said legs being corrugated and at least one of said legs having a flattened portion back of the corrugated portion which imparts a 80 spring action to the pin and causes the legs normally to be in contact with each other, said leg having the flattened portion being of round cross-section in front of said flattened portion. 85

2. A hairpin comprising a single piece of material of round cross-section folded intermediate of its ends to form two legs, at least one of said legs being corrugated, the other leg being in contact with said first leg and at least one of said legs being provided near the fold with a portion of flattened cross-section to impart springiness thereto, said leg being of decreased width on opposite sides of said portion of flattened cross-section. 90

3. A hairpin comprising a single piece of material of round cross-section folded intermediate of its ends to form two legs, at least one of said legs being corrugated and the other leg being in contact therewith, and both of said legs having short portions of flattened cross-section creating spring portions which normally hold the legs in contact with each other. 100

4. A hairpin comprising a single piece of material of round cross-section folded intermediate of its ends to form two legs, both of said legs being corrugated throughout a substantial portion of their length, and both of said legs being provided intermediate of their ends with short portions of flattened cross-section which impart springiness to the legs. 110

5. A hairpin comprising a single piece of material folded intermediate of its ends to form two legs, one of said legs being of round cross-section at the fold and having a corrugated portion extending through a considerable part of its length and being of round cross-section where the same is corrugated but being out of round between the fold and the corrugated portion so as to create a short springy region therein. 120

6. A hairpin comprising a single piece of material folded intermediate of its ends to 125

form two legs, one of said legs being in contact with the other and being of round cross-section in the portion adjacent the fold and throughout the major portion of its length but having a deformed portion out of round creating a short springy region intermediate of the ends of said leg.

7. A hairpin comprising a single piece of material of round cross-section folded intermediate of its ends to form two legs, both of said legs being corrugated and of round cross-section throughout a substantial portion of their length, and both of said legs being provided intermediate of their ends with portions of flattened cross-section which impart springiness to the legs and hold them normally in contact with each other, said flattened portions being located adjacent the butt end of the pin.

8. A hairpin comprising a single piece of material of round cross-section folded intermediate of its ends to form two legs, one of said legs being longer than the other, the shorter leg being corrugated and of round cross-section throughout a portion of its length and having in the rear of the corrugated round portion a spring portion of flattened cross-section.

9. A hairpin comprising a single piece of material of round cross-section folded intermediate of its ends to form two legs, one of said legs being longer than the other, the free ends of said legs being divergent, the short leg being corrugated and of round cross-section back of its free end portion and being provided back of the corrugated round portion and near the butt end with a spring portion tending to hold said leg in contact with the long leg.

10. A hairpin constructed of a single piece of material folded intermediate of its ends to form two legs, the folded or butt end being of round cross-section but merging into spring portions of flattened cross-section, and said spring portions of flattened cross-section merging into portions of round cross-section located toward the free ends of the legs.

11. A hairpin comprising a single piece of material folded intermediate of its ends to form two legs, one of said legs being in contact with the other, and the first leg having at the butt or folded part thereof a portion of round cross-section and toward the free end thereof a portion of round cross-section, but intermediate said portions a spring portion of flattened cross-section.

In witness whereof, I have hereunto set my hand this 26th day of October, 1931.

IRVING H. PECK.
